UNITED STATES PATENT OFFICE.

CHARLES H. DAVIS, OF WORCESTER, MASSACHUSETTS; BERTHA B. DAVIS EXECUTRIX
OF CHARLES H. DAVIS, DECEASED.

DENTAL TOOL.

1,299,137.

Specification of Letters Patent.

Patented Apr. 1, 1919.

Application filed February 2, 1915. Serial No. 5,790.

To all whom it may concern:

Be it known that I, CHARLES H. DAVIS, a citizen of the United States, residing at Worcester, in the county of Worcester, State 5 of Massachusetts, have invented a certain new and useful Improvement in Dental Tools, of which the following is a specification, reference being had therein to the accompanying drawings.

10 This invention relates to dental tools, but more particularly to such as are used in cleaning, polishing or grinding teeth, and has for its object to provide a structure which is more efficient than any devices of 15 a similar nature heretofore known.

In the case of tooth cleaning devices consisting wholly or partially of flexible or semi-flexible material, and particularly those having at least the central portion of 20 rubber or other pliable or resilient material, great difficulty has been found in securing means for holding the same so that relative rotation is impossible. that such pliable or resilient centers shall not be cut by the 25 holding means, and that freedom of action shall be obtained.

One feature of the present invention is the mandrel in which the hub of the tooth operating tool is bound by the forcing of the 30 flexible or resilient material of such hub substantially away from the axis of the binding screw or other member performing this function. A second feature is the formation of the mandrel head with indentations or perforations therein in which the 35 flexible material of the hub of the tooth operating tool is forced or held by the action of the binding member. Another feature is the formation upon the hub of the 40 tooth operating tool of projections adapted to enter corresponding indentations or orifices in the mandrel, so that such tool will be rigidly positioned and maintained therein to facilitate the insertion of the binding 45 screw or other similar means, and when bound therein by the action of such screw to act in conjunction with the inner or binding face of the mandrel to prevent relative rotation of the mandrel and tooth operating 50 tool. A further feature of the invention is the tool having a rigid or substantially rigid operating portion and a flexible or resilient central portion or hub which will provide a firm grip upon the mandrel and

will permit of freedom of action of the tool 55 and rocking of such tool relative to the axis of the mandrel.

Many other features and advantages of the invention will be described hereinafter and included in the claims. 60

Referring to the drawings:

Figure 1 is a side elevation of one embodiment of the invention.

Fig. 2, central longitudinal section of the embodiment shown in Fig. 1 with the parts 65 in their relative position for assembling.

Fig. 3, same as Fig. 2, but with the parts assembled.

Fig. 4, side elevation of the tooth operating tool detached from the mandrel, as will 70 be fully described hereinafter.

Fig. 5, side elevation of a modified form of the invention, as will be fully described hereinafter.

Fig. 6, side elevation of the tooth operating tool in the embodiment of the invention shown in Fig. 5, as will be fully described hereinafter. 75

Fig. 7 central longitudinal section of a further modification of the invention, as 80 will be fully described hereinafter.

Fig. 8, side elevation of a modified form of the tooth operating tool, as will be fully described hereinafter. 85

In the embodiment of the invention shown in Figs. 1 to 4 inclusive, the invention is shown to comprise a mandrel 20 formed with a shank 21 adapted to be inserted in the usual form of rotary shaft machine found in dental operating rooms. 90 At the forward end of this shank is formed the head 22 which is adapted to receive and hold the hub of the tooth operating tool 23 here shown of the rubber cup variety. For the sake of simplicity of description this 95 tooth operating tool will be hereinafter referred to as the tool, and while this tool is shown of the cup variety it should be clearly understood that any of the many forms of dental tools might be substituted therefor, provided they are constructed with a flexible, resilient or expandible hub or central portion, or the evident equivalent thereof. 100

In this embodiment of the invention, the head is formed substantially cup shaped 105 with the outer rim of the cup extending substantially parallel to the axis of the mandrel, and it has been found to be advanta-

geous that the inner or operating face of such head should be substantially cup shaped or with its side walls projecting forwardly from the center or base of this face of the 5 mandrel for the reasons which will be readily evident from the following description. In the inside walls of this head are here formed one or more indentations or orifices 24 to receive the hub of the tool 23, though 10 these indentations or orifices are not essential to the construction as will be described in connection with the embodiment shown in Fig. 7. While it is in no way essential that these indentations 24 should 15 pass through the walls of the head, it has been found that this is the easiest method of forming them. Projecting forwardly from the base of the operating face of the mandrel is preferably constructed a member 20 25 through which passes the threaded hole 26 concentric with the axis of the mandrel. This threaded hole is adapted to receive the binding screw 26^a and the outer extremity of the member 25 forms a seat for the head 25 of this screw to prevent such head from advancing into contact with the base of the operating face of the mandrel. This seat for the head of the screw has been found to be very advantageous in preventing the 30 screw from advancing sufficiently to force its way entirely through the hub of a tool in which the flexible or resilient portion of the hub is larger than the diameter of the head of the screw. When indentations or 35 orifices 24 are formed in the head of the mandrel, it has been found to be somewhat advantageous to form corresponding projections 27 on the hub of the tool for the reason which has been stated in connection 40 with the indentations 24, but these are not essential as will be fully explained in connection with the embodiment shown in Fig. 7.

In Fig. 5 is shown a modification of the 45 invention in which the indentations or orifices 28 in the head 29 of the mandrel 30 are oblong instead of round as was the case of the embodiment shown in Figs. 1 to 4 inclusive. With this form of indentations 50 or orifices it is advantageous to use a tool having projections 31 thereon corresponding to and preferably fitting the indentations or orifices 28 as is shown in Fig. 6 of the drawings.

55 In the embodiment shown in Fig. 7 the structure is substantially identical with those shown in Figs. 1 to 6 inclusive with the exception that no indentations or orifices are formed in the head 32 of the mandrel 33. In 60 this figure the tool is shown entirely composed of rubber and through the center thereof is an orifice 34 through which passes the binding screw 35 and this central orifice 34 is preferably of smaller diameter than the 65 head 36 of the screw so that when such screw

is advanced in the tapped hole in the mandrel in the usual manner, the hub is expanded by the wedging action of the head and such head advances until it becomes seated in the member 37. This expanding of the hub by 70 the action of the head of the binding screw or pin forces the outer wall 38 of the hub against the opposing inner face of the mandrel and thus causes the tool to be bound about the periphery of such hub as well as 75 against the base of the cup face of the mandrel. It has heretofore been common practice to bind a tool upon a mandrel with a binding screw, and no invention is claimed on this structure when broadly construed, 80 but it is believed that in all cases heretofore the binding has been performed by pressure exerted substantially parallel with the axis of the binding screw only. Where such material as rubber having certain adhesive or 85 gripping qualities is used, it has been found that generally sufficient hold will be obtained on the tool to prevent relative rotation of such tool and the mandrel, but the use of an indented or perforated head gives additional 90 holding power which insures absolute hold. In the latter case not only are the projections upon the hub, if these are used, held within such indentations or orifices, but a certain amount of material forming the body of the 95 hub is forced therein as will be readily evident.

In Fig. 8 of the drawings is shown a modified form of tool in which the cup shaped or operating portion 39 thereof is 100 constructed of abrasive material and the central portion or hub 40 is of flexible or resilient material to permit of ready use in the mandrel described in Figs. 1, 2, 3, 5 and 7. In this form of tool the hub may be formed 105 separate from the operating portion and either cemented, vulcanized or otherwise fastened thereto, or they may be formed integral and the operative portion provided with the abrasive material and vulcanized or 110 otherwise treated to produce a rigid or semi-rigid portion if desired.

In all the embodiments herein shown and described, it is advisable to make the head of the screw with its upper and lower faces, or 115 particularly the lower one either conical or rounded to facilitate the hub expanding action thereof and to obviate any possibility of the rubber or other hub material being cut by the sharp edges thereof, though it should 120 be clearly understood that this is not essential to the construction.

What I claim as my invention and desire to secure by Letters Patent is:—

1. In a device of the class described, a tool 125 provided with a projecting hub, a mandrel having a socket formed therein to receive the projecting portion of said hub, the walls of said socket being indented, and means for expanding said hub within said socket. 130

2. As an article of manufacture, a tool, a mandrel provided with an axial perforation, a headed pin adapted to pass through said tool and have its forward portion held within said perforation to secure said tool to said mandrel, and means projecting from the binding face of said mandrel for maintaining the head of such pin at an interval from

said face when the tool is in its bound position in the mandrel. 10

In testimony whereof I affix my signature in the presence of two witnesses.

CHARLES H. DAVIS.
